IRONING MACHINE CONTROL MECHANISM

William H. Bradley, Fort Wayne, Ind., assignor
to Horton Manufacturing Company, Fort
Wayne, Ind., a corporation of Indiana

Application February 21, 1946, Serial No. 649,180

2 Claims. (Cl. 38—61.)

1

The invention relates generally to ironing machines and more particularly to an ironing machine of the character shown in my copending application Serial No. 540,672, filed June 16, 1944, and comprising a pair of relatively shiftable ironing elements, one of which is a roll, and power-driven mechanism adapted to effect such shifting movement and to drive the roll.

The general object of the invention is to provide an ironing machine of the foregoing general character, having a novel manual control means for the power-driven mechanism, which is movable in one direction to effect shifting of the shiftable element, and in another direction to stop rotation of the roll.

Another object is to provide an ironing machine of the foregoing general character, having a novel manual control means for the power driven mechanism, which is movable in one direction to cause the shiftable element to be moved toward or from the other element, the power driven mechanism being automatically connected to the roll when the shiftable element is moved toward the other and disconnected when the shiftable element is moved away from the other, said control means being operable in another direction to disconnect said mechanism from the roll when the two elements are in engagement.

A further object is to provide an ironing machine of the foregoing general character, having a novel control means movable in opposite directions from a neutral or idle position respectively for effecting shifting movement of the shiftable element and for stopping rotation of the roll when the two elements are in engagement, said control means being adapted to automatically return to its neutral or idle position when released after being moved in either direction.

Other objects and advantages will become apparent from the following description taken in connection with the accompanying drawings, in which:

Figure 1 is an end elevational view of an ironing machine embodying the features of the invention.

Fig. 2 is a fragmentary sectional view taken on the line 2—2 of Fig. 3.

Fig. 3 is a fragmentary side elevational view, partly in section, of the machine shown in Fig. 1.

Fig. 4 is a perspective view of the parts utilized in controlling the machine.

The ironing machine shown in the present application as well as in the above referred to copending application Serial No. 540,672 comprises a base 10 provided with a head structure, indi-

cated generally at 11, secured to the base adjacent one end thereof and extending upwardly therefrom. Mounted on a shaft carried by the head 11 is an ironing element in the form of a roll 12 provided with the usual padding and on which the articles to be ironed are placed. Cooperating with the roll 12 is a second ironing element in the form of a shoe 13 shiftably supported by an arm 14 for movement toward and from the roll. The arm 14 is carried by a rock-shaft 15 located in and extending lengthwise of the base 10. While, in the structure herein shown, the shoe is the shiftable element, the invention is of such scope as to cover a machine in which the roll is shiftable.

In the specific structure shown in my copending application, the head 11 comprises a supporting member 16 enclosed by a shroud 17 of any preferred external appearance and design. The supporting member 16 has its upper end formed as part of a motor casing 20 to support a motor 21 and has secured thereto a gear casing 22. To drive the roll, the motor 21 operates power driven mechanism comprising a shaft provided with a pinion 23 meshing with a gear 24 mounted on a shaft 25. The shaft 25 is provided with a pinion 26 meshing with a gear 27 loosely mounted on a stub shaft 30. The gear 27 is adapted to be connected by a clutch 31 to the shaft 30. The shaft 30 has rigidly formed thereon a pinion 32 meshing with a gear 33 mounted on the roll-supporting shaft, indicated at 34. Thus, when the clutch 31 is connected, the roll will be driven at a reduced speed by the motor 21.

The motor and power driven mechanism are also utilized to effect shifting movement of the shoe 13 toward and from the roll 12. To this end, the shaft 25 is provided with a second pinion 35 meshing with a gear 36 loosely mounted on a shaft 37. Also mounted on the shaft 37 and rotatable with the gear 36 is a toothed member 40. Secured to the shaft 37 adjacent the toothed member 40 is a disk 41 carrying a clutch finger 42 adapted to engage the toothed member 40 under control of the operator. Thus, when the finger 42 is in engagement with the toothed member 40, the shaft 37 is rotated.

The shaft 37 also carries a pinion 43 meshing with a cam drive gear 44 secured to a shaft 45. The shaft 45 carries a four-lobed cam 46 adapted, when rotated, to swing a lever 47 mounted on a hollow shaft 50. The lever 47 is pivotally connected to an intermediate lever 51 secured to a rockshaft 52. The rockshaft 52 projects through the wall of the gear casing and at its outer end

is provided with a lever 53 connected by a link 54 to a shoe-actuating lever 55. A spring 56 is connected to the pivotal connection of the link 54 and the lever 55 and tends to hold the lever 47 in engagement with the cam 46. The shoe-actuating lever 55 is bent to extend downwardly into the base 10 and is connected to the rock-shaft 15 for carrying the shoe toward and from the roll. An energy-storing device, indicated generally at 56, is mounted in the gear casing to cooperate with the cam 46 to compensate for and counterbalance the effect of a spring 57 in the shoe-supporting arm 14 so that such spring will not tend to cause an overdrive of the cam 46 when the shoe moves away from the roll and will not place an excessive load on the drive when the shoe is moving toward the roll.

The clutch 31 controlling the operation of the roll 12 is normally urged into engagement by a spring (not shown) and is adapted to be disengaged by a disengaging member comprising one arm 63 of a bell crank 64. The other arm of the bell crank 64 extends toward the lever 51 and is adapted to be held in clutch-disengaging position by an extension 65 on the end of the pivotal connection between the levers 47 and 51 when these two levers are so positioned that the shoe 13 is out of engagement with the roll. Thus, the roll will be stopped when the shoe is out of engagement therewith.

The clutch controlling the shifting of the shoe and comprising the finger 42 and the tooth member 40 is adapted to be disengaged by a disengaging member 70. The disengaging member 70 comprises a strip of metal and has an edge portion which normally lies in the path of the finger 42 to hold the finger out of engagement with the toothed member 40, but when the disengaging member 70 is shifted out of the plane of the finger 42, a spring (not shown) causes the finger 42 to engage the toothed member 40 and thus effect rotation of the cam 46. The disengaging member 70 is adapted to be shifted out of the plane of the clutch finger and then to be released so that, when the clutch finger 42 has made one revolution, it is reengaged by the edge portion of the disengaging member 70 and shifted out of engagement with the toothed member 40.

The present invention relates to a novel control means for controlling the roll clutch 31 and the shoe shifting clutch comprising the finger 42 and toothed member 40. Said control means, in its preferred form, comprises a rockshaft 71 mounted in the tubular shaft 50. The rockshaft 71 extends into the gear casing 22 beyond the inner end of the tubular shaft 50 and carries a rockable member 72 (see Fig. 2). The rockable member 72 is preferably a flat piece of metal having one end 73 engageable with a cam surface 74 provided by a bulge formed on the disengaging member 70. When the rockable member 72 is swung upwardly, as viewed in Fig. 2, the end 73 thereby acts against the cam surface 74 and functions to shift the disengaging member 70 out of the plane of the finger 42 so that the latter, under pressure of its spring, will engage the toothed member 40 to drive the cam 46 and thereby effect shifting movement of the shoe 13 either toward or from the roll, as the case may be. The member 72 then is permitted to move back into its initial position and the disengaging member 70 thereupon moves back into the plane of the clutch finger 42 so that the latter will be disengaged from the toothed member 40 after one revolution. In this period, the cam 46 has been rotated through

one eighth of a turn and the shoe 13 is shifted either toward or from the roll.

The foregoing mode of operation is that which is employed for ordinary ironing. When the shoe is shifted away from the roll, the extension 65 moves the bell crank 64 to disengage the roll clutch 31 and thereby stop the roll. When the member 72 next shifts the disengaging member 70, engagement of the shoe-shifting clutch causes movement of the shoe toward the roll, and the extension 65 moves out of engagement with the bell crank 64 so that the spring of the roll clutch 31 functions to cause engagement of such clutch. The roll will, therefore, rotate when the shoe is in engagement therewith.

The machine may also be used for pressing by preventing rotation of the roll when the shoe is in engagement therewith. To this end, the rockable member 72 is provided with a finger or hook-shaped portion 75 adapted to engage the arm of the bell crank 64 which is normally engaged by the extension 65. Thus, assuming that the shoe 13 is in engagement with the roll, by swinging the rockable member 72 clockwise as viewed in Fig. 2, the finger portion 75 swings the bell crank 64 to effect disengagement of the roll clutch 31. The roll 31 will thereby be held stationary and articles may be pressed between the shoe and the roll, as long as member 72 is held in this position.

It will be noted from the foregoing that the rockable member 72 extends between the two disengaging members 70 and 64 and is adapted to be rocked in one direction to actuate one of the disengaging members and in the opposite direction to actuate the other disengaging members. To rock the shaft 71 carrying the member 72, the outer end of the shaft 71 is provided with a hand lever 80. In the present instance, the outer end of the shaft 71 is bent at a right angle to constitute the hand lever 80. The hand lever is adapted to extend through a slot 81 provided in the shroud 17 and is formed on its outer end with a finger portion 82.

In the preferred construction, the hand lever 80 is adapted to be automatically held in its neutral or intermediate position out of engagement with both of the disengaging members 64 and 70. To this end, I provide a pair of springs 83 secured to the interior of the shroud 17 as by being engaged over hooks 84 therein. The springs 83 extend toward each other and are secured at their adjacent ends through an aperture 85 in the hand lever 80. Thus, when the hand lever is moved in either direction, it will be automatically returned by the springs 83 to its intermediate position.

For pressing, with the shoe in engagement with the roll, the operator merely lifts the lever 82, which swings the bell crank to disengage the roll clutch. Thus, the operator can interrupt the ironing mode of operation and utilize the machine for pressing at any time. Should the operator desire to move the shoe toward the roll without permitting the roll to start, all the operator has to do is to first depress the lever 82 to effect connection of the shoe shifting clutch and then raise the lever 82 to hold the bell crank 64 against swinging as the pin 65 moves away from the bell crank.

From the foregoing, it will be apparent that the hand lever 80 may be moved in one direction to effect shifting of the shiftable element and in the opposite direction to stop rotation of the roll. With the particular arrangement herein shown,

the outer end of the hand lever 80 is adapted to be depressed to cause shifting of the shoe 13 as in normal ironing work. When it is desired to use the machine for pressing, the outer end of the hand lever 80 is adapted to be lifted to cause disengagement of the roll clutch and thereby permit the shoe 13 to be in engagement with the roll when the latter is stopped. The hand lever 80 automatically returns to its intermediate position whenever the operator releases it, so that it is ready for either mode of operation.

I claim:

1. An ironing machine comprising a pair of relatively shiftable elements, one being a roll, power driven mechanism for rotating said roll and for shifting one of said elements toward and from the other including a first clutch engageable to effect shifting movement of the element, and a second clutch engageable to effect rotation of the roll, a clutch control member for the first clutch shiftable bodily to effect engagement of the first clutch and having a cam surface, a clutch control member for the second clutch swingable to cause disengagement of the second clutch, a manually actuatable plate having an end portion and a finger portion and swingable only in one direction in a plane to move said end portion into engagement with said cam surface to bodily shift the clutch control member for the first clutch and swingable only in the opposite direction in said plane to move said finger portion into engagement with the clutch control member for the second clutch for swinging the clutch control member, whereby opposite movements of said plate are required for actuating the respective clutch-control members, and a pair of stops operatively associated with said plate to limit its movement to two spaced opposite positions for actuating the respective clutch-control members.

2. An ironing machine comprising a pair of relatively shiftable ironing elements, one being a

roll, a base, casing means extending upwardly from the base at one end thereof and having a rounded head portion, power driven mechanism mounted in said head portion for rotating said roll and for shifting one of said elements toward and from the other including a pair of clutches for controlling such rotation and for effecting such shifting, and a pair of disengaging members for the respective clutches, a member located in said head portion and swingable in one direction to move the disengaging member for the clutch controlling the rotation of the roll and in the opposite direction to move the disengaging member for the clutch for effecting the shifting movement, said swingable member being normally positioned between said disengaging members whereby opposite movements of said swingable member are required for moving the respective disengaging members, said head portion having a slot extending circumferentially thereof, and a hand lever extending generally radially from said head portion through said slot and angularly movable to the limits of said slot to actuate said swingable member.
